M. KAZAWA.

TRAFFIC INDICATOR.

APPLICATION FILED MAR. 15, 1915.

Patented Apr. 4, 1916.

UNITED STATES PATENT OFFICE.

MASUNOSUKE KAZAWA, OF SEATTLE, WASHINGTON.

TRAFFIC-INDICATOR.

1,178,018.

Specification of Letters Patent.

Patented Apr. 4, 1916.

Application filed March 15, 1915. Serial No. 14,503.

To all whom it may concern:

Be it known that I, MASUNOSUKE KAZAWA, a subject of the Emperor of Japan, and a resident of the city of Seattle, in the county 5 of King and State of Washington, have invented certain new and useful Improvements in Traffic-Indicators, of which the following is a specification.

My invention consists of a traffic indicator or a device to be mounted upon vehicles 10 to indicate the direction in which it is intended to steer the vehicle.

The object of my invention is to produce a device of reasonable cost and which may 15 be conveniently operated to clearly indicate the direction in which it is intended to turn the vehicle, so that other traffic in the street may control its movements accordingly and collisions be thus avoided.

20 The particular features of which my invention consists will be defined by the claims terminating this specification.

In the accompanying drawing I have shown my invention embodied in the forms 25 of construction which are now preferred by me.

Figure 1 is a section through the device taken on a plane extending from front to rear. Fig. 2 is a section taken upon the 30 line 2—2 of Fig. 1. Fig. 3 is a section, which, in the main, is upon a central horizontal plane of Fig. 2, as shown by line 3—3, one side of the device being broken away. Fig. 4 is a front elevation of the 35 device showing the targets and the windows at which they are exposed, portions of the device being broken away, and Fig. 5 is a sectional view taken from the point indicated by the characters 5—5 of Fig. 1.

40 My device is mounted within a casing which, as shown, consists of a cylinder, or ring 1, provided with a back 10, and a front 11, the latter being provided with openings 12, 13 and 14, these serving as windows 45 through which the targets, which are within the casing, may be seen when placed in proper position. A frame 2, which is supported within the device, carries upon it the means by which the targets are operated. The targets consist of three disks 30, 31 and 32, all of which are pivoted to swing 50 upon a common pivot 3, the latter being placed at the center of the casing. Each target consists of a disk member, and which,

as herein shown, is of a circular outline, and 55 an arm 33 by which it is connected with the common pivot.

Three targets are shown, one, the center one, being shown as provided with a letter S. This target is normally exposed before 60 the center window 12 and, when seen, indicates that the vehicle is intending to proceed straight ahead. The other targets 30, 32 are normally held at points intermediate the center window 12 and the side windows 65 13, 14. The side windows 13, 14 are separated from the center window 12 a sufficient distance, so that in the normal positions of the targets 30 and 32 the latter may not be seen. I have shown the windows as separated 70 from each other 90°, and the targets in their position of rest, as being separated from each other 45°. The arms of the two outer targets 30 and 32, engage with stops, as pins 35, which prevent their swinging 75 nearer the center than that occupied in the position of rest. When the device is operated, the center target 31 and one of the end targets is swung away from the center in a direction which will raise the outer target 80 85 to its window 13 or 14, as the case may be, the other end target is not moved from its position of rest. The means for securing this result are as follows: Secured upon the shaft 3 is a pinion 4 and a disk or equivalent member 40. The disk 40 has a flange 41 which is provided with notches to receive the arms 33 of the various targets. Secured to shaft 3 is a pointer 42, which is outside or in front of the face or dial 11. This 90 pointer, normally, is in a dependent position, pointing to the window 12. This may be moved through 90° to have it point to either of the windows 13 or 14, while the targets 30 and 32, which are exposed at 95 these windows, need only to move through 45°. In consequence of this, the arm of the center target 31 is placed in a slot which will permit of movement of the disk 40 through 45° before it will engage the arm 100 33. The flange 41 of this disk is also provided with two slots which receive the arms of the respective targets 30 and 32. These slots, when the disk is in the position of rest, are of such length that they extend 45° 105 from the arm of each target 30 and 32 toward the center, and 90° in the other direction. Therefore, when the disk is turned in

one direction, it will not pick up the end target 30 or 32, as the case may be, until after it has moved 45° , that is, until the pointer 42 comes into line with the arm 33 of this target, and it will not engage the arm of the other end target to move it at all. Also it will not engage the arm of the center target 31 until it has moved through 45° and will then swing it into the position 10 before occupied by the end target which is being moved.

The means for turning the pointer and the disk 40, are as follows: An arm 5 is pivoted at 50 and has its free end branched to form 15 a yoke 51, which is secured to the ends of the rack bar 52, which rack bar meshes with the pinion 4. Another arm 6 is pivoted at 60, at the opposite side of the center and is connected with the arm 5 by means of a slot 61, 20 through which passes a securing pin 62. The pivot 6, may conveniently be a shaft which extends outside the case and which is turned by any suitable or convenient means, as, for instance, a small hand wheel 63, 25 which turning means may be located at any convenient accessible point. When the arm 6 is swung upon its pivot it will swing the arm 5, which carries the rack 52, thereby turning the pinion 4 and disk 40 by which 30 the targets are moved. These parts are automatically returned to their center position by means of spring 7, which are secured to the ends of the arm 6 and to threaded bolts 70, which extend through the 35 wall of the case and are adjusted in position by means of thumb nuts 71. By adjusting these anchor bolts, the tension upon the springs 7 may be adjusted so as to draw these parts to their center position whenever 40 released.

Having thus described my invention, what I claim as new, and desire to secure by Letters Patent of the United States of America, is:—

45 1. A traffic indicator having a front face provided with three windows, three signal targets pivoted back of said face and adapted to swing to expose each at its respective window, stops engaging the end targets of the series to prevent swinging 50 toward the center position beyond fixed points, and a target swinging member pivoted concentric with the targets and having a slack engagement with all said targets,

said slack being greater for the end targets 55 than for the center one.

2. A traffic indicator having a face or dial having three windows positioned at successive points separated by 90° , three targets pivoted concentric with said windows 60 and adapted to be displayed thereat, stops preventing the end targets of the series from being exposed at the center window, an exteriorly disposed pointer pivoted concentric with the targets, means for swinging said 65 pointer, and means connecting said pointer operating means with the targets to swing the latter half the amount of swing of the pointer.

3. A traffic indicator having a face or dial 70 having three windows positioned at successive points separated by 90° , three targets pivoted concentric with said windows and adapted to be displayed thereat, stops preventing the end targets of the series from 75 being exposed at the center window, an exteriorly disposed pointer pivoted concentric with the targets, means for swinging said pointer, and a member inward of the face connected to swing with the pointer and having stops engaging the targets to swing them, said stops being spaced to permit swinging of the pointer 45° before engaging the targets.

4. A traffic indicator having a face or dial 80 having three windows positioned at successive points separated by 90° , three targets pivoted concentric with said windows and adapted to be displayed thereat, stops preventing the end targets of the series from 85 being exposed at the center window, an exteriorly disposed pointer pivoted concentric with the targets, means for swinging said pointer, and a member inward of the face 90 connected to swing with the pointer and having stops engaging the targets to swing them, said stops being spaced to permit swinging of the pointer 45° before engaging the targets, and fixed stops engaging the end targets of the series to prevent them from 95 swinging toward the center from their position of rest.

Signed at Seattle, Washington, this 17th day of February, 1915.

MASUNOSUKE KAZAWA.
